METHOD AND APPARATUS FOR TREATING HAIR

Filed May 20, 1932

INVENTOR
Ernst Heinicke
BY
Gern C. Heinicke
ATTORNEY

UNITED STATES PATENT OFFICE

ERNST HEINICKE, OF NEW YORK, N. Y.

METHOD AND APPARATUS FOR TREATING HAIR

Application filed May 20, 1932. Serial No. 612,419.

This invention relates to a new and improved method, composition and apparatus for treating hair for imparting a permanent wave thereto.

5 It is the principal object of my invention to provide a permanent wave within the shortest possible time without developing excessive heat harmful to the hair and uncomfortable to the person, without the use of 10 electricity or special apparatus.

Another object of my invention is the provision of a novel and improved compound developing readily the heat required while the hair is protected against undue drying and 15 from becoming brittle in order to maintain it in a healthy condition.

A further object of my invention is the provision of a novel and inexpensive, yet efficient method of treating the hair for imparting a permanent wave thereto without the slightest inconvenience to the person treated, and one which will last for a considerable time.

A still further object of my invention is 25 the provision of suitable pads containing the heat developing ingredients and a protecting cover therefor.

These and other objects and advantages of my invention will become more fully known 30 as the description thereof proceeds, and will then be more specifically defined in the appended claims.

In the accompanying drawing forming a material part of this disclosure:

35 Fig. 1 illustrates the construction of the inner core of my novel and improved apparatus for treating hair according to my method for imparting a permanent wave thereto.

40 Fig. 2 is a perspective view of the outer member or roll used in the production of a permanent wave, according to my method, spread out.

Fig. 3 is an end view of said outer member.

45 Fig. 4 is a detail view of a roll or outer member.

Fig. 5 is a sectional end view of the entire roll with outer and inner member.

50 In the practical embodiment of my invention, strands of the hair to be treated are

first wound about a stick or rod 10, as indicated at 11, and tied to the rod by means of a string or cord 12. About the hair is then wound a strip of textile fabric, such as for instance cotton flannel interlining 13 soaked 55 in an ammonia lotion for protecting and softening the hair.

The interlining 13 is then covered by a strip of tin foil 14 and formed into a roll, constituting an inner member.

60 The outer member into which the inner member is placed, contains the heating body comprising a tin foil pocket 15, in which a flannel bag 16 contains a compound, preferably in powder form composed of a mixture 65 of calcium oxide or live lime and calcium hydrate or slaked lime in certain proportions, as will hereinafter be more fully explained.

70 The tin foil pocket 15 is provided with a plurality of openings 17 allowing the penetration of water into the pocket, which is covered by an outer cover 18 preferably of tin foil and also having numerous perforations 19. The entire body is then rolled up into a paper cover, preferably wax paper 20. 75 In the practical execution of my method I use for the construction of the heating element preferably 55% of live lime, 30% of calcium hydrate, 10% calcium oxide and 5% of a water and ammonia lotion.

80 In use, the hair is first wound about the rod 10 as shown in Figure 1, and then secured thereto by means of the band 12 the end near to the scalp of this band is clamped into a slot 21 of the rod while the opposite end is knotted 85 about the rod. A protecting shield having first been placed on the hair strand near the scalp and is held in position by any suitable customary clamping means. The interlining 13 is then soaked with an ammonia water 90 solution or lotion tending to protect and soften the hair, and the cover of tin foil 14 is then wound about the rod and hair and held thereon in any suitable manner.

95 Then the roll 20 is prepared for endwise fitting over the hair, by soaking the pad cover 18 and pocket 15 with water or other suitable fluid to develop heat within the pocket by the slaking of the lime while the calcium hydrate will prevent the development of an excess of 100

heat. The pad 15 and cover 18 are then rolled into the roll 20 of wax paper and placed over the hair wound about the rod. The roll is left about 15 minutes on the hair and upon its removal it will be found that a permanent wave has been formed in the hair.

It will be understood that I have disclosed the preferred form of my device only as one example of the many possible ways to practically construct the same and that I may make such changes in the general arrangement and the construction of the minor details, as well as in the ingredients used and in their proportions of mixture as come within the scope of the appended claims without departure from the spirit of my invention and the principles involved.

Having thus described my invention, what I claim as new and desire to secure by Letters Patent is:

1. In a device of the character described a heat developing body comprising a fabric bag containing calcium oxide and calcium hydrate, a perforated tin foil cover therefor in a perforated tin foil wrapper, and a wax paper outer cover for the whole.

2. A compound for creating heat in hair waving apparatus consisting of 55% of lime, 30% of calcium hydrate, 10% of calcium oxide and 5% of a water and ammonia lotion.

3. In the making of a permanent hair wave, the process which consists in soaking a protecting cover for the hair with a water-ammonia lotion, and winding about the same a heating roll containing calcium hydrate and calcium oxide in a water ammonia lotion, and subjecting the hair to 15 minutes treatment.

Signed at New York, in the county of New York, and State of New York, this 19th day of May, A. D. 1932.

ERNST HEINICKE.
